UNITED STATES PATENT OFFICE

2,001,716

ROCK DRILL

Elmer G. Gartin, Claremont, N. H., assignor to
 Sullivan Machinery Company, a corporation of
 Massachusetts

Application October 1, 1929, Serial No. 396,560

10 Claims. (Cl. 121—9)

This invention relates to rock drills, and more particularly, but not exclusively, relates to improved feeding mechanism for a rock drill of the mounted drifter type.

An object of this invention is to provide an improved rock drill feeding mechanism. Another object is to provide an improved and very compact rock drill feeding mechanism of the pressure fluid actuated type. Yet another object is to provide an improved pressure fluid operated feeding mechanism for such a drill wherein a relatively long feed is obtained without materially increasing the over-all length of the drill. A further object is to provide in such a drill a pressure fluid actuated feeding motor of the cylinder and piston type including improved connections between the drilling tool and the movable feeding element whereby the feeding range of the feeding motor is substantially doubled without materially increasing the over-all length of the drill. A further object is to provide an improved pressure fluid actuated feeding mechanism for a rock drill wherein a pressure fluid actuated feeding motor is utilized and including cable and pulley connections between the drilling tool and the feeding motor whereby without increasing the over-all length of the feeding motor a relatively long feed is obtained. A still further object is to provide an improved rock drill feeding mechanism including a guide shell on which the drilling tool is slidably guided and improved and exceedingly compact pressure fluid operated mechanism for positively feeding the drilling tool forward and rearward relative to the guide shell. These and other objects and advantages of this invention will, however, hereinafter more fully appear.

In the accompanying drawings there is shown for purposes of illustration one form which the invention may assume in practice.

In these drawings,—

Fig. 1 is a side elevational view of a rock drill having incorporated therein the illustrative embodiment of the improved feeding mechanism.

Fig. 2 is a transverse vertical sectional view taken substantially on line 2—2 of Fig. 4.

Fig. 3 is a transverse vertical sectional view taken substantially on line 3—3 of Fig. 4.

Fig. 4 is a central, longitudinally extending, vertical developed sectional view taken through the improved feeding mechanism, the drilling tool being shown in side elevation.

Fig. 5 is a transverse vertical sectional view taken on line 5—5 of Fig. 4.

Fig. 6 is a detail sectional view of the valve

mechanism shown in Fig. 4, the valve being shown in its reverse position.

In this illustrative construction I have shown a rock drill of the mounted drifter type including a hammer type drilling tool 1 of a standard construction including a drill steel 2 adapted to be percussively actuated by a usual hammer motor 3. As is usual in drilling tools of the drifter type the cylinder of the hammer motor 3 has formed integral therewith lateral guide members or gibs 4 (see Fig. 2) which are slidably mounted within parallel guideways 5 formed on a guide shell 6. This guide shell has a usual swivel base or plate 7 adapted to be mounted within a usual trunnion mounting on a tripod or column in a well known manner. As clearly shown in Figs. 1 and 2, secured by parallel longitudinally extending side members or rods 8 to the rear end of the guide shell 6 is a transverse head or block 9, this member 9 being spaced longitudinally from the guide shell by means of spacing sleeves 10 encircling the side rods 8. Arranged within a transverse conical bore 11 formed in the head member 9 is the conical end of a feed piston rod 12, this conical end of the piston rod being rigidly secured within the bore in the member 9 by means of a nut 13 threadedly connected at 14 to the rear end of the piston rod. Rigidly secured by a threaded connection 15 to the forward end of the piston rod 12 is a feed piston 16 arranged within a bore 17 formed in a feed cylinder 18. As shown in Fig. 4, this feed cylinder extends longitudinally of the guide shell 6 and is slidably supported within the guide shell. The feed cylinder is provided with front and rear cylinder heads 19 and 20, the rear cylinder head 20 having a central bore 21 through which the piston rod 12 extends. A usual cup packing 22 carried by the rear cylinder head engages the external periphery of the feed piston rod to prevent leakage of pressure fluid from the cylinder bore. Surrounding the piston rod and slidably mounted thereon is an adjustable support 24 abutting at its forward end against the rear cylinder head. The support 24 is provided with a stub shaft 26 on which is journaled a pulley or sheave 27, the latter being held in position on the shaft by means of a screw and washer connection 28. The front cylinder head 19 is provided with a forward cylindrical extension 29 having mounted thereon an adjustable support 30, similar to the support 24, and which abuts at its rear end against the front cylinder head. Journaled on the support 30 is a pulley or sheave 32 arranged in the same manner as the pulley 27 heretofore described. As clearly shown in Figs. 2 and 3, the guide shell 6 is cut

away at 33 throughout a substantial portion of its length to provide clearance for the pulleys 27 and 32 as hereinafter described. Passing around the pulleys 27 and 32 is an endless flexible element, 5 herein a cable 34. The cable 34 is secured at 35 by an adjustable clamping bolt 36 to a projecting portion 37 formed on the rear head 38 of the hammer motor 3 of the drilling tool. This cable is also attached by a clamping bolt 39 (see Fig. 3) 10 to the guide shell 6. The cable 34 maintains the pulleys in the position shown although it is evident that if desired the pulley supports 24 and 33 may be held in a suitable manner against rotative movement relative to the supports on which they 15 are mounted.

The improved mechanism for controlling the fluid distribution means for the feed cylinder herein includes a rotary throttle valve 40 arranged within a transverse bore 41 formed in the 20 head member 9 to which the piston rod of the stationary feed piston 12 is secured. This valve has a usual operating handle 42. Formed in the head member 9 are parallel passages 43 and 44 communicating with the bore 41 and with parallel passages 45 and 46 respectively formed in the piston rod 12. The passage 45 extends 25 throughout the length of the piston rod 12 and communicates at its forward end with the front end of the feed cylinder bore at the front side 30 of the feed piston, while the passage 46 communicates through a lateral port 47 with the rear end of the feed cylinder bore at the rear side of the feed piston. The valve 40 has formed therein a radial port 48 communicating with the central supply passage 50 within the valve. Also 35 formed on the exterior periphery of the valve are exhaust grooves 51 and 52 which are communicable with exhaust ports 53 and 54 formed in the valve casing. Pressure fluid is supplied 40 to the pressure chamber 50 in the throttle valve through a flexible hose connection 55 which is connected to the pressure chamber within a throttle valve 56 which controls the supply of pressure fluid to the hammer motor 3. This hose connection 45 is of such length as to permit the drilling tool to be fed into its extreme forward position relative to the guide shell. When the valve is in the position shown in Fig. 4, pressure fluid is admitted from the central supply chamber 50 in 50 the valve through the port 48, passage 43 in the member 9, and passage 45 in the piston rod to the feed cylinder bore at the front end of the feed piston. At the same time the feed cylinder bore at the rear side of the feed piston is connected to exhaust through port 47, passage 46 in the feed piston rod, passage 44 in the member 9, the exhaust groove 52 in the valve and exhaust port 54. As a result, the feed cylinder 55 is fed forward relative to the guide shell 6, moving therewith the pulleys 27 and 32. As the feed cylinder 18 and the pulleys 27 and 32 move forward, the cable 34 due to its connection at 39 to the guide shell and to the drilling tool causes the latter to be fed forward along the guideways 60 on the shell at a feeding speed substantially twice the rate of travel of the feed cylinder, the pulleys and cables forming a connection between the feed cylinder and the drilling tool which materially increases the feed. When the throttle valve 40 is turned into its opposite position as shown in Fig. 6, the feed cylinder bore at the front side of the feed piston is exhausted to atmosphere, while the rear end of the feed cylinder bore is 65 connected to the pressure fluid supply and as a

result the feed cylinder is fed rearward relative to the stationary feed piston.

In the operation of the improved rock drill feeding mechanism the guide shell 6 is set up adjacent the working face with its swivel support 7 mounted within the usual trunnion mounting of a tripod or column. When the parts are in the position shown in Fig. 1 with the feed cylinder and drilling tool in their rearmost position, the pressure fluid is admitted to the cylinder 10 bore at the front side of the feed piston and as a result the feed cylinder is fed forward relative to the guide shell 6. As the feed cylinder moves forward the pulleys 27 and 32 move therewith and these pulleys together with their co-operating cable 34, which is attached to the guide shell and the drilling tool, cause the latter to be fed forward at a feeding speed substantially twice the rate of movement of said cylinder. When the hole is completed or if it is desired 20 to change steels, the throttle valve 40 is turned into its reverse position and the feed cylinder bore at the front side of the piston is vented to atmosphere, while pressure fluid is admitted to the cylinder bore at the rear side of the piston. 25 As a result the feed cylinder and drilling tool are fed rearward relative to the guide shell to the position shown in Fig. 1.

As a result of this invention an improved rock drill feeding mechanism is provided wherein a 30 relatively long feed is obtained without materially increasing the over-all length of the drill. It will further be noted that by providing the reciprocable feed cylinder and a stationary feed piston arranged in the manner disclosed herein 35 and by employing a cable and pulley connection between the reciprocable feed cylinder and the drilling tool, the feeding speed of the tool is substantially increased, the feeding movement of the drilling tool being substantially twice that of the 40 feed cylinder. These and other uses and advantages of the improved feeding mechanism will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended 50 claims.

What I claim as new and desire to secure by Letters Patent is:

1. In a rock drill, a guide shell, a drilling tool guided thereon, and feeding mechanism for the 55 drilling tool including a reciprocable cylinder and a piston element and a connection between said reciprocable cylinder element and the drilling tool whereby the feeding speed of the latter is substantially multiplied.

2. In a rock drill, a guide shell, a drilling tool guided thereon, and feeding mechanism for the drilling tool including a reciprocable cylinder and a piston element and a cable and pulley connection between said reciprocable cylinder element and the drilling tool whereby the feeding speed of the latter is substantially multiplied.

3. In a rock drill, a guide shell, a drilling tool guided thereon, and feeding mechanism for the drilling tool including relatively reciprocable cylinder and piston elements, said cylinder element being guided by said shell, and speed multiplying connections between said cylinder element and said drilling tool.

4. In a rock drill, a guide shell, a drilling tool 75

guided thereon, and feeding mechanism for the drilling tool including relatively reciprocable cylinder and piston elements, said cylinder element being guided by said shell, and speed multiplying connections between said cylinder element and said drilling tool including a cable and pulley connection.

5. In a rock drill, a guide shell, a drilling tool guided thereon, and feeding mechanism for the 10 drilling tool including relatively reciprocable cylinder and piston elements, said cylinder element being guided by said shell, and speed multiplying connections between said cylinder element and said drilling tool including a pulley carried by 15 said cylinder and a cooperating cable attached to the drilling tool.

6. In a rock drill, a guide shell, a drilling tool guided thereon, and feeding mechanism for the drilling tool including relatively reciprocable cylinder and piston elements, said cylinder element being guided by said shell, and speed multiplying 20 connections between said cylinder element and said drilling tool including a pulley carried by 25 said cylinder and a cooperating cable attached to the drilling tool and said guide shell.

7. In a rock drill, a guide shell, a drilling tool guided thereon, and feeding mechanism for the drilling tool including relatively reciprocable cylinder and piston elements, said cylinder element 30 being guided by said shell, and speed multiplying connections between said cylinder element and said drilling tool including pulleys moving with said cylinder and a cooperating cable attached to the drilling tool.

35. 8. In a rock drill, a guide shell, a drilling tool guided thereon, and feeding mechanism for the drilling tool including piston and cylinder elements one of which is movable, a pulley mounted on the front end of the movable one of said elements, a flexible portion secured at one of its 40 ends to said shell and passing forwardly from such point of connection around said pulley and then rearwardly, means for attaching the rearwardly extending strand of said flexible portion 45 to the rear end of said drilling tool thereby to effect a multiplied forward feed of the drilling tool, and means for feeding the drilling tool rear-

wardly with a multiplied effect including a pulley carried by the rear end of said movable element, and a flexible portion secured to the rear end of the drilling tool and passing rearwardly over said latter pulley and thence forwardly to a point 5 where it is secured to the front end of said shell.

9. In a rock drilling mechanism, a guide shell, a rock drill slidably guided thereon, and pressure fluid actuated mechanism for feeding the rock 10 drill relative to said guide shell including relatively reciprocable cylinder and piston elements, said piston element remaining stationary during reciprocation of said feed cylinder, and connections between said reciprocable feed cylinder element and the rock drill whereby upon movement of the cylinder at a certain speed the rock drill is fed at a substantially higher speed, said connections including guide pulleys, one mounted at each end of said feed cylinder element, flexible 20 feeding means guided by said pulleys and extending therebetween and including flexible feeding portions arranged parallel and adjacent to the feed cylinder, and means for connecting said flexible feeding portions to said guide shell and rock 25 drill.

10. In a rock drilling mechanism, a guide shell, a rock drill slidably guided thereon, and pressure fluid actuated mechanism for feeding the rock drill relative to said guide shell including relatively reciprocable cylinder and piston elements, said piston element remaining stationary during reciprocation of said feed cylinder, and connections 30 between said reciprocable feed cylinder element and the rock drill whereby upon movement of the cylinder at a certain speed the rock drill is fed at a substantially higher speed, said connections including guide pulleys, one mounted at each end of said feed cylinder element, endless flexible 35 feeding means guided by said pulleys and extending therebetween, said flexible feeding means having parallel portions arranged parallel with and adjacent to the feed cylinder element, and means for connecting said parallel portions to 40 said guide shell and rock drill respectively. 45

ELMER G. GARTIN.
